[57] CLAIM

The ornamental design for a boat-mounted signal light
to indicate the presence of water skiers, as shown and
described.

DESCRIPTION

FIG. 1 is a side perspective view of a boat mounted
safety light for water skiers showing my new design;
FIG. 2 is a top plan view thereof on a reduced scale;
FIG. 3 is a bottom plan view thereof on a reduced scale;
FIG. 4 is an elevational view thereof on a reduced scale
taken from the side opposite that shown in FIG. 1.

FIG 3

FIG 4
